AUTOGRAPHIC REGISTER MACHINE

Howard W. Lewis, Newton Lower Falls, Mass.

Application February 4, 1944, Serial No. 521,099

6 Claims. (Cl. 282—5)

This invention relates to autographic registers of the general type adapted to handle a continuous series of record sheets in strip or web form and has for its object the improvement and simplification of the web feeding means for such machines.

The typical form of manifold strips designed for use in the present machine is illustrated in United States patent to Wiswall 1,534,478, April 21, 1925. As therein shown, a plurality of superposed strips of record sheets are perforated at intervals throughout their length with a perforation at a corresponding place in each record sheet adapted to be engaged by suitable feeding means for being advanced over the writing table of an autographic register.

Heretofore the means for imparting a feed stroke to the superposed strips, viz., the advancing of a set of record sheets into writing position on the table, has involved the use of crank and gearing mechanism or other relatively complicated devices. In the present improvement, the feed stroke for the superposed strips is accomplished by extremely simple mechanism having a minimum of moving parts and involving on the operator's part merely a push with his finger lengthwise of the table against an exposed operating peg. Also as will appear, the arrangement is such that the action of the operator in advancing the sheets for a feed stroke will serve to effect and maintain accurate registration of said sheets in their superposed relation during their travel over the table into writing position.

Further improvements and advantages of the present invention will become apparent in the following more detailed description taken in connection with the accompanying drawing, which show a preferred embodiment thereof and in which,

Fig. 1 is a perspective view of the autographic register machine;

Fig. 2 is a plan view of said machine with certain parts broken away for clearness;

Fig. 3 is a longitudinal, sectional view along line 3—3 of Fig. 2 looking in the direction of the arrows;

Fig. 4 is an enlarged fragmentary detailed side view of the web stripping means; and

Fig. 5 is a fragmentary detail in plan of the same.

Referring more particularly to the drawing, 1 indicates the usual cabinet or housing for the complete autographic register machine. At the top of said cabinet is a writing table or platform 2 which may have a removable cover member 3 slightly spaced above the same. Cover 3 is formed with a cutout portion or window, the outlines of which are indicated at 4, for exposing in writing position 5 on the table, the topmost sheet of the superposed manifold strips. As shown

more particularly in Fig. 3, the supply 6 of strips in manifold form may be contained within a compartment 7 at the forward end of the cabinet, from which the several superposed strips as indicated at 8 are guided over a drum surface 9 and along the top of the table 2 to be finally deposited in folded form within a rear compartment 10 of said cabinet. At the rear of the cabinet, one or more of the topmost strips such as 11 may be separated into sheets in the usual manner.

It is customary in these machines to provide interleaved carbon sheets between the several record sheets at the position where the strips lie upon the writing table. In the present embodiment as shown in Fig. 2, there are one or more superposed carbon sheet tie members, the topmost of which is indicated at 12 mounted over suitable pins 13 at each forward side of said writing table. Extending rearwardly from each tie member such as 12, is a carbon sheet 14 and the rear end of said carbon sheet is indicated in dotted line at 15. It will be understood that additional carbon tie members and sheets may lie below the one shown for being interleaved between the record sheets of the manifold strips in the usual manner.

The writing position on the table 2 is at the place enclosed by the window opening 4, and the means for imparting a feed stroke to said manifold strips to bring successive record sheets thereof into said writing position will now be described. Mounted within the cabinet below the top thereof are a pair of rotatable belt pulleys 16 and 17 each slightly flanged and adapted to support and guide thereon an endless feed belt 18, said belt being preferably in the form of a flat metal band extending from the front pulley 16 over the top of the table 2 and down off the rear end thereof onto said pulley 17. The band or belt 18 need only be frictionally engaged upon said pulleys and carries fixed thereto a plurality of projecting push-pegs such as 19 spaced apart equally on said belt and adapted to register with and project through the spaced perforations of the manifold strips 8. The pulleys 16 and 17 are preferably of equal size and the forward pulley 16 as shown is mounted in the cabinet to guide the belt 18 from its top periphery in a straight line over the table 2. The rear pulley 17 is mounted in the cabinet with its peripheral surface slightly below the top of the table 2 so that the belt 18 in traveling off the table to the periphery of said pulley 17 takes a slightly downward rearward slant. The purpose of this is to help in disengaging the pegs of the belt from the perforations in the manifold strips 8 at the end of a feed stroke. For this purpose also the pegs 19 are slightly conical in shape as shown.

A rearward extension of the table 2 is provided

at 20, preferably in the same horizontal plane as said table 2, said extension having a removable cover member 21 slightly spaced above the same as shown in Fig. 1. This rearward extension 20 is formed with a slotted portion 22 indicated in dotted lines in Fig. 5 which frames the upper peripheral portion of the pulley 17 as shown in Fig. 3. The cover member 21 of the rear extension 20 is formed at its forward end with an upturned lip 23 for guiding the straight line travel of the manifold strips over the table and at the right hand forward corner of said member 21 as shown in Fig. 1 is formed a curled up portion 24 located directly over the rear end of the slot 22 which serves as a stop for the finger of the operator at the completion of the feed stroke as will be hereafter described. Slightly to the rear of said lip portion 23 and stop portion 24 of said cover member 21 is a knife edge portion 25 against which some or all of said strips such as 11 may be torn to separate record sheets therefrom.

A leaf spring 26 serving as a hold back pawl for said feed belt is mounted on an inside partition 27 of said cabinet in a position to be successively engaged by the pegs on the said belt 18 and prevent any retrograde movement of said feed belt at the completion of a feed stroke. While I have shown a hold back device in its simplest form, it will be understood that other equally suitable devices may be employed. Occasionally it might be desired to move the strips purposely backward on the table by the feed belt and for this purpose a throw-out device (not shown) for the pawl 26 should be provided.

The feed belt is preferably provided with a minimum of three pegs 19, 19a, and 19b, but a greater number may be used if desired, limited only by the spacing of the holes in the manifold strips. In the embodiment shown, it will be understood that the lengthwise spacing of the holes in the manifold strips is the full length of a feed stroke.

It is desired that a peg 19 shall emerge from within the cabinet housing and be exposed for actuation by the operator's finger at the beginning of a feed stroke, in other words at the forward end of the writing table 2. Simultaneously the peg 19a in advance should be at the rear end of a feed stroke as shown ready to be submerged in said housing upon the next feed stroke actuation. For this purpose the centers of the pulleys 16 and 17 are spaced apart the length of said feed stroke and vertically in line with the beginning and end of said stroke respectively so that the pegs 19 and 19a when brought to the top center of the corresponding pulley periphery will be in the position desired. To take care of the proper length of the belt for the distribution of three pegs thereon as shown, the pulleys 16 and 17 are of a diameter each having a circumference which is equal to the distance of a feed stroke, namely, from the center to center of said pulleys.

The operation of the feed mechanism is as follows: Assuming the parts in position as shown in Fig. 3, the operator for discharging a completed set of record sheets from the table 2 and bringing a fresh set of sheets into writing position thereon, will place his finger or thumb against the push-peg 19 and push the same rearwardly with a downward pressure against the table until the finger strikes the stop member 24, a full stroke. The finger of the operator in so pushing against the peg 19 will not only push said peg forwardly against the perforated por-

tions of all the superposed strips to bring them into proper register, but also by a simultaneous downward pressure will serve to keep said strips down on the table and against the feed belt. 5 In other words, there will be no possibility during this forward stroke, of the strips becoming disengaged from the push-pegs. Furthermore at the end of the stroke the finger in coming against the stop 24 will assist in pressing the peg downwardly beneath said stop so as to be stripped from engagement with the holes in the superposed webs. The stripping action of said webs from the driving peg 19 will be assisted by the framing of the slot 22 of the extension table 20 which during the submergence of said belt down through the slot will maintain the superposed webs in their horizontal straight line position on the table and rearward extension.

The construction heretofore described may be modified in various equivalent respects to give the same results. For example it may be desirable in some cases to position the feed belt at the left side of the writing table so as to have the right hand more free for writing. Furthermore, it is not essential that the feed belt actually run over the top of the writing table for engagement with the under side of the web. For instance, the feed belt may operate in a groove of the table, below the top surface thereof, the essential requirement being that it should be in a substantially coinciding relation with the top of the table throughout its length. Additional pegs and perforations may be employed to give a partial feed stroke as well as a full stroke. Also, in addition to the pegs which engage and feed the web other pegs or tabs may be fixed to the side of the belt for a push by the operator in imparting the feed stroke. However, in its most simplified form, the invention contemplates the use of the same 40 pegs both for feeding the web and for being pushed by the operator. The means for stripping the web from the pegs may be accomplished by means guiding the web upwardly so as to be lifted off the pegs instead of guiding the belt and pegs downwardly as shown. The means for guiding the discharge of the web from the writing table comprising the horizontal extension 20 is merely one form for purposes of illustration and it should be understood that various modifications thereof may be made to facilitate the guiding of the discharged web into the storage compartment 10 and provide for the separation of those portions of the web which are to be torn off. I do not attempt to show all the modifications that may be made in the construction shown.

I claim:

1. In an autographic register in combination, a housing having a writing table thereon, means for 60 guiding over said writing table successive record sheets in the form of a continuous web, said web being perforated at intervals lengthwise thereof with perforations at corresponding positions in each record sheet, means to impart a feed stroke 65 to said web for bringing a fresh record sheet into writing position on said table and for discharging a completed record sheet therefrom comprising an endless feed belt having a run located beneath said web in a substantially coinciding relation 70 with the top of said writing table and push-pegs projecting from said belt in position for actuation by the operator's finger throughout the length of a feed stroke in causing travel of said belt from one end to the other of said writing table and a 75 stop abutment at the discharge end of said writing

table said abutment projecting upwardly therefrom as high as the top of the pegs adapted for engagement by the operator's finger at the completion of a feed stroke.

2. In an autographic register in combination, a housing having a writing table thereon, means for guiding over said writing table successive record sheets in the form of a continuous web, said web being perforated at intervals lengthwise thereof with perforations at corresponding positions in each record sheet, means to impart a feed stroke to said web for bringing a fresh record sheet into writing position on said table and for discharging a completed record sheet therefrom, comprising an endless feed belt with its upper run located beneath said web in a substantially coinciding relation with the top of said writing table, the lower run of said belt being located below said table and within said housing, push-pegs carried by said belt in register with the perforations of said web and adapted to project through said perforations during the feed stroke on said web and guiding means for said belt to cause the push-pegs carried thereby to emerge from said housing into exposed position for actuation by the operator at the start of a feed stroke and to submerge into said housing at the end of a feed stroke and means to prevent retrograde movement of said web at the completion of a feed stroke comprising a pawl positioned below the lower run of said feed belt engageable by the pegs on said belt.

3. In an autographic register in combination, a housing having a writing table thereon, means for guiding over said writing table successive record sheets in the form of a continuous web, said web being perforated at intervals lengthwise thereof with perforations at corresponding positions in each record sheet, means to impart a feed stroke to said web for bringing a fresh record sheet into writing position on said table and for discharging a completed record sheet therefrom, comprising an endless feed belt with its upper run located beneath said web in a substantially coinciding relation with the top of said writing table, the lower run of said belt being located below said table and within said housing, push-pegs carried by said belt in register with the perforations of said web and adapted to project through said perforations during the feed stroke on said web and guiding means for said belt to cause the push-pegs carried thereby to emerge from said housing into exposed position for actuation by the operator's finger at the start of a feed stroke and to submerge into said housing at the end of a feed stroke and a stop abutment at the discharge end of said writing table said abutment projecting upwardly therefrom as high as the top of the pegs adapted for engagement by the operator's finger at the completion of a feed stroke.

4. In an autographic register in combination, a housing having a writing table thereon, means for guiding over said writing table successive record sheets in the form of a continuous web, said web being perforated at intervals lengthwise thereof with perforations at corresponding positions in each record sheet, means to impart a feed stroke to said web for bringing a fresh record sheet into writing position on said table and for discharging a completed record sheet therefrom, comprising an endless feed belt with its upper run located beneath said web in a substantially coinciding relation with the top of said writing table, the lower run of said belt being located below said table and within said housing, push-pegs carried by said belt in register with the perforations of said web and adapted to project through said perforations

during the feed stroke on said web and guiding means for said belt to cause the push-pegs carried thereby to emerge from said housing into exposed position for actuation by the operator's finger at the start of a feed stroke and to submerge into said housing at the end of a feed stroke and a stop abutment at the discharge end of said writing table said abutment projecting upwardly therefrom as high as the top of the pegs adapted for engagement by the operator's finger at the completion of a feed stroke, and a knife edge at the rear of said stop abutment against which separate sheets may be torn from said web.

5. In an autographic register in combination, a housing having a writing table thereon, means for guiding over said writing table successive record sheets in the form of a continuous web, said web being perforated at intervals lengthwise thereof with perforations at corresponding positions in each record sheet, means to impart a feed stroke to said web for bringing a fresh record sheet into writing position on said table and for discharging a completed record sheet therefrom, comprising an endless feed belt with its upper run located beneath said web, in a substantially coinciding relation with the top of said writing table, the lower run of said belt being located below said table and within said housing, push-pegs carried by said belt in register with the perforations of said web and adapted to project through said perforations during the feed stroke on said web, guide pulleys for said belt one at each end of said table to cause the push-pegs carried by said belt to emerge from said housing for actuation by the operator at the beginning of a feed stroke and to submerge into said housing at the end of a feed stroke, the guide pulley for said belt at the discharge end of said table having its belt engaging periphery slightly below the level of said table so as to guide the feed belt in a downward rearward inclination as it leaves said table.

6. In an autographic register in combination, a housing having a writing table thereon, means for guiding over said writing table successive record sheets in the form of a continuous web, said web being perforated at intervals lengthwise thereof with perforations at corresponding positions in each record sheet, means to impart a feed stroke to said web for bringing a fresh record sheet into writing position on said table and for discharging a completed record sheet therefrom, comprising an endless feed belt with its upper run located beneath said web in a substantially coinciding relation with the top of said writing table, the lower run of said belt being located below said table and within said housing, push-pegs carried by said belt in register with the perforations of said web and adapted to project through said perforations during the feed stroke on said web, guide pulleys for said belt one at each end of said table to cause the push-pegs carried by said belt to emerge from said housing for actuation by the operator at the beginning of a feed stroke and to submerge into said housing at the end of a feed stroke, the guide pulley at the discharge end of said table having its belt engaging periphery slightly below the level of said table so as to guide the feed belt in a downward rearward inclination as it leaves said table, and an extension of said writing table arranged to guide said web in being discharged from said writing table, said extension being formed with a slotted opening through which the upper run of said belt submerges as it leaves said writing table.
